Arthur B. Conklin,
ATTORNEY

UNITED STATES PATENT OFFICE

JOHN H. CONKLIN, OF EAST HAMPTON, CONNECTICUT

TOY TELEPHONE

Application filed February 12, 1931. Serial No. 515,156.

My invention relates to that class of toys made in imitation of telephones and similar apparatus, and an object of my invention, among others, is the production of a toy in imitation of the latter styles of telephone apparatus, both in appearance, as to operation and in the sounds produced by and emanating therefrom.

One form of a telephone apparatus embodying my invention, and in the construction and use of which the objects herein set out, as well as others, may be attained is illustrated in the accompanying drawing, in which—

15 Figure 1 is a view in front elevation of my improved telephone apparatus, with parts broken away to show construction.

Figure 2 is a view in section through the base illustrating the manner of controlling 20 the speed of rotation of the dial.

Figure 3 is a view in side elevation of my improved toy telephone with the hand bar cut in cross section.

Figure 4 is a detail top view of a portion 25 of the base with the dialing disk removed.

Figure 5 is a view in section on a plane denoted by the dotted line 5—5 of Figure 2.

My improved telephone apparatus illustrated and described herein quite closely simulates, both in operation and in results produced, those obtained in the ordinary use of regular telephones, that is, the signal is effected without disturbing other than the signal apparatus, the calling or dialing operation is performed without affect from or upon other parts of the instrument, and talking effects are produced from the receiver in the regular operation of placing the hand telephone set in use.

40 In the accompanying drawing the numeral 5 denotes the base of my improved telephone, 5 a post rising therefrom and surmounted by a support or rest 7 on which the hand telephone is placed when not in use. A signal bell 8 of any ordinary construction is secured to the post 6 and has a thumb lever 9 as a means for operating it. The base of the bell has a bracket 10 terminating in a cap 11 fitting over the top of the post 6, and the support or rest 7 sets upon said cap, a bolt

passing downwardly through the rest, cap, post and base and secured by a nut underneath the post uniting all said parts firmly together.

55 A bridge 12 is secured inside of the base to the top thereof, and a shaft 13 is rotatably supported by the bridge and the base, projecting above the top of the latter. A gear 14 is secured to the shaft and meshes with a pinion 15 located between the bridge and base. A scape wheel 16 is rigidly secured to the pinion and a pallet 17 is engaged with the scape wheel in a manner common to structures of this class and operates to regulate the speed 60 of rotation of a dialing disk 18 secured to the projecting end of the shaft 13 above the base 5.

65 The bridge is held in place by prongs 19 projecting through the base and overturned thereabove, and an indicating disk 20 is secured at its edges under said prongs, said disk having indicating characters underlying 70 openings 21 in the disk 18 in a manner simulating the indicating characters underneath 75 the dial disk of a regular telephone set.

75 A lug 22 projects from one edge of the disk 18 and acts by contact with a finger stop 23 to limit return movement of the dial under the influence of a spring 24 having one end secured to the shaft 13 and its other end engaged with one of several spring holding 80 prongs 25 projecting upwardly from the base within and against the edge of the hole in the center of the disk 20, said prongs also serving to retain said disk in position.

85 The hand telephone set comprises an imitation of a receiver 26 at one end and a transmitter 27 at the other end as embodied in the hand set of a regular telephone. These 90 members are preferably constructed of sheet metal and are secured to opposite ends of a bar 28, also formed of sheet metal. A sounding device 29 is housed within the receiver 26 and operates to automatically produce a 95 sound, particularly when the receiver is placed against the ear of a person as in the act of using the hand set. This sounding device may be one of any number of devices of this sort that are readily purchased in the 100 open market. That employed herein is of

the bellows type from which air is forced through a reed or similar sound producing device. This bellows is located in a case 30 and includes a weighted end 31 shown here-
5 in as extended out of the open end of the case when the hand set is in position on the rest 7 and not in use.

The member mentioned herein as a sound-
10 ing device is commonly referred to in the trade as a "voice", this being located in the earpiece or receiver 26, which earpiece is in the same relative position with respect to the mouthpiece or transmitter 27 as in a regular telephone set now in common use.

15 In operation the handle or hand bar 28 is grasped to remove the hand set from the rest, and the earpiece or receiver is placed against the ear. This act inverts the receiver to such degree that the weighted end of the bellows passes into the case, thereby expelling the air from the bellows through the reed and causing a sound which may simulate a "voice", as though reproduced in the earpiece or receiver. A cord 32 is extended from the base 20 to the hand set to simulate the connecting wire cord of a regular telephone set.

In accordance with the provisions of the patent statutes I have described the principles of operation of my invention together 30 with the device which I now consider to represent the best embodiment thereof; but I desire to have it understood that the device shown is only illustrative and that the invention may be carried out by other means and applied to uses other than those above set out.

I claim:

1. A toy telephone including a base provided with means for supporting a receiver, an earpiece simulating a receiver adapted to be supported by said base and to be removed therefrom and inverted for use, and a gravity actuated sounding device located within said earpiece and arranged to be sounded when said earpiece is inverted.

45 2. A toy telephone including a base provided with means for supporting a receiver, a receiver adapted to be supported by said base and to be removed therefrom and inverted for use, and a "voice" located in said receiver and caused to sound when the position of the receiver is changed in placing it against the ear.

50 3. A toy telephone including a base provided with a rest for a hand set, a hand set adapted to be received upon said rest and comprising a receiver and a transmitter at opposite ends of a handle bar adapted for use only when inverted, and a gravity actuated sounding device located within said receiver and adapted to be sounded when said receiver is inverted.

55 4. A toy telephone including a base provided with means to support a receiver, a receiver adapted to be supported by said base and to be removed therefrom and inverted

for use, a simulation of a dialing set including a dial rotatably mounted on the base, and a gravity actuated sounding device located in said receiver and adapted to be sounded when said receiver is inverted.

70 5. A toy telephone including a base provided with means for supporting a receiver, an ear piece simulating a receiver adapted to be supported by said base and to be removed therefrom and inverted for use, and a gravity actuated sounding device so positioned in the receiver that it will sound when the receiver is changed from a horizontal to a vertical position to simulate the reception of a message.

75 6. A toy telephone including a base provided with means to support a receiver, an ear piece simulating a receiver adapted to be supported by said base and to be removed therefrom and inverted for use, and a gravity actuated sounding device comprising a weighted collapsible member arranged to collapse and thereby sound when the receiver is changed from a horizontal position on its support to a vertical position when placed 80 against the ear to simulate the reception of a message.

85 JOHN H. CONKLIN.
